CLAIM

The ornamental design for stand for supporting an elevated grill, as shown and described.

DESCRIPTION

FIG. 1 is a perspective view of a stand for supporting an elevated grill showing my new design;

FIG. 2 is a right side elevational view thereof;

FIG. 3 is a left side elevational view thereof;

FIG. 4 is a front end elevational view thereof;

FIG. 5 is a rear end elevational view thereof;

FIG. 6 is a top plan view thereof; and

FIG. 7 is a bottom plan view thereof.

The broken line showing of a grill in FIGS. 1-3 is for illustrative purposes only and forms no part of the claimed design.
